UNITED STATES PATENT OFFICE.

JOHN BRANDWOOD, THOMAS BRANDWOOD, AND EDWARD BRANDWOOD, OF BURY,
ENGLAND.

APPARATUS FOR DYEING AND LIKE TREATMENT OF TEXTILE MATERIAL.

1,125,803.

Specification of Letters Patent.

Patented Jan. 19, 1915.

Application filed February 12, 1913. Serial No. 747,962.

To all whom it may concern:

Be it known that we, JOHN BRANDWOOD, THOMAS BRANDWOOD, and EDWARD BRANDWOOD, subjects of the King of Great Britain and Ireland, and residents of Bury, in the county of Lancaster, England, have invented a new and useful Apparatus for Dyeing and like Treatment of Textile Material, of which the following is a specification.

10 This invention relates to improvements in the construction of the perforated beams or cylinders upon which yarns, threads, cloths or the like wound thereon are subjected to treatment by liquids, gases, or vapors passing therethrough. Such treatment will be 15 hereinafter generally referred to as dyeing.

The main objects in view are to obtain a beam or cylinder of large dimensions and capacity without undue cost and use of the 20 special metal which has to be used in many processes; which will combine lightness and strength; and which is so formed as to easily provide a liquid tight seal to insure passage 25 of the liquid through the material on the beam.

The accompanying drawings illustrate a perforated beam constructed according to this invention.

Figure 1 shows it partly in section and 30 partly in elevation in the vertical position in which it is preferably placed for the dyeing of the warps or equivalents which are wound upon it. Fig. 2 represents the beam in end elevation.

35 A sheet of perforated metal of a nature suitable to the process in which it is to be used, is bent to form a cylindrical shell A. Some of the perforations which are formed all over it are shown at B. Inside this shell 40 at suitable distances apart are supporting rings C which closely fit into the shell and are riveted or otherwise secured to it. Such rings may have any convenient form in cross section, but such form shown in Fig. 1 is 45 generally suitable.

Near to each end of the cylindrical shell is placed a flat ring D of the special metal closely fitting around the shell. These rings 50 are the flanges of the beam. To hold them securely in place and to give sufficient strength to them, angle rings E of sufficient 55 solidity are riveted to the ends of the shell and have the rings or flanges D also riveted to them. The angle rings E may be formed

integrally with spokes F and with hubs G 55 by means of which the beams can be mounted for rotation.

When in use for dyeing the beam stands vertically on one end within the dyeing vat. The edge e of the angle ring E beds down 60 upon an indiarubber or other packing washer through which passes an inlet pipe to admit dye liquor under pressure to the interior of the cylindrical shell. The upper end of the shell may be closed by a cap 65 fitting over it which cap is subjected to external screw pressure to not only hold the cap in place but also to press the ring E on to the lower end of the shell firmly on its seat and to retain it there. 70

In a modified form of beam one end only may have the spokes or equivalent openings to permit flow of liquor and the other end may be permanently closed.

Other modes of using the improved beam 75 than vertically as described may be employed.

In dyeing it is essential that those parts of the beam with which the yarns or fabrics come into contact should be of a metal or 80 material which is unacted upon by the dye and will not affect the yarn or the like in contact with it. Those parts of the beam which do not come into contact with yarn or the like may be of cheaper metal such as 85 iron. Thus the angle rings C and E may be of iron or steel.

For bleaching it is preferred to form all parts of the beam of the special suitable metal. In this case each ring or flange may 90 be formed in a single piece with the supporting member.

The seam along the cylinder shell where the edges of the perforated sheet are brought together may be secured by a metal strip 95 laid along it in the interior of the shell. Rivets then hold them together and the strip may be drilled through where necessary to provide perforations which are coincident with those in the shell. 100

What we claim is:—

1. A perforated beam for use in the fluid treatment of textile materials wound thereon, such beam comprising a thin perforated metallic shell, members for attaching such 105 shell to a concentrically contained shaft, supporting rings secured to the interior of the shell between such shaft attaching mem-

bers, and a fluid tight joint member concentric to such shell, substantially as set forth.

2. A perforated beam for use in the fluid treatment of textile materials wound thereon, such beam comprising a thin perforated metallic shell, members for attaching such shell to a concentrically contained shaft, supporting rings secured to the interior of the shell between such shaft attaching members, a fluid tight joint member concentric to such shell, flat rings encircling such shell and forming flanges thereon and rings external to such flanges secured both to the flanges and the shell, substantially as set forth.

3. A perforated beam for use in the fluid treatment of textile materials wound thereon, such beam comprising a thin perforated metallic shell, members for attaching such shell to a concentrically contained shaft, supporting rings secured to the interior of the shell between such shaft attaching members, a fluid tight joint member concentric to such shell, flat rings encircling such shell and forming flanges thereon, rings external to such flanges secured both to the flanges and the shell, and fluid tight jointing mem-

bers formed on such rings, substantially as set forth.

4. A perforated beam for use in the fluid treatment of textile materials wound thereon, such beam comprising a thin perforated metallic shell, members for attaching such shell to a concentrically contained shaft, supporting rings secured to the interior of the shell between such shaft attaching members, a fluid tight joint member concentric to such shell, flat rings encircling such shell and forming flanges thereon, rings external to such flanges secured both to the flanges and the shell, such rings being formed integral with the shaft carrying means and with fluid tight jointing members, substantially as set forth.

In witness whereof we have hereunto set our hands in the presence of two subscribing witnesses.

JOHN BRANDWOOD.
THOMAS BRANDWOOD.
EDWARD BRANDWOOD.
